CLAIM

The ornamental design for an automobile front end, as shown and described.

DESCRIPTION

FIG. 1 is a perspective view of the front, top and right side of an automobile front end showing our new design;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom view thereof.

The portions of the automobile front end shown in broken lines are for illustrative purposes only and form no part of the claimed design.
